UNITED STATES PATENT OFFICE.

BRUNO KNIFFLER, OF CLEVELAND, OHIO.

FLOUR-DRESSER.

SPECIFICATION forming part of Letters Patent No. 381,020, dated April 10, 1888.

Application filed November 24, 1886. Serial No. 219,828. (No model.)

To all whom it may concern:

Be it known that I, BRUNO KNIFFLER, of Cleveland, in the county of Cuyahoga and State of Ohio, have invented new and useful 5 Improvements in Flour-Dressers; and I do hereby declare that the following is a full, clear, and exact description thereof, reference being had to the accompanying drawings, which form a part of this specification.

10 This invention relates to certain new and useful improvements in the construction of flour-dressers.

Heretofore a class of reels known as common "six-ribbed reels" has been in almost 15 universal use among manufacturers of flour, and, these reels being hexagonal, the method of bringing the chop in contact with the bolting-cloth is very imperfect. Only a part of the bolting-surface is in actual use. Consequently 20 the capacity is comparatively small to the large surface. Through the falling of the chop from one side of the hexagonal reel to the other specky particles of the chop are bolted and mixed with the flour. The six-ribbed 25 reel is now gradually becoming superseded by the cylindrical reel, in which a far superior bolting action is produced by letting the chop gently slide over the face of the cloth.

My improved reel belongs to the latter class; 30 and the object of my invention is to provide a construction in which the chop is brought in sliding contact with as large as possible an extent of bolting-cloth, so as to increase the capacity of the reel and improve the quality 35 of the material bolted, and which, furthermore, is especially adapted to permit the conversion of the old-style six-ribbed reel into the improved class to which my reel belongs, so as to make the transition less costly to the 40 miller.

To this end my invention consists in the general construction and arrangement of the parts, and also in the peculiar construction of buckets rigidly secured to the heads within 45 the reel and arranged in proximity to the bolting-cloth, by means of which in the rotation of the reel the chop is made to slide over the bolting-cloth on the descending side of the reel as well as on the ascending side, and which 50 also permits the chop to readily collect at the bottom of the reel.

Figure 1 is a vertical central cross-section of my improved flour-dresser. Fig. 2 is an enlarged vertical cross-section showing the method of securing the parts together. Fig. 55 3 is a central longitudinal section of the same.

In the drawings, A represents the shaft, which is, in the usual way, supported upon proper bearings, (not shown,) and B are a series of lag-screws, by means of which the hoops 60 which carry the bolting-cloth C are extended and held in place.

D are a series of stelliform-shaped supports, preferably sawed out from boards and secured to the shaft A, for the purpose of supporting 65 the buckets, and as many of these supports may be employed as are necessary, preferably at equal distances apart upon the shaft.

E are a series of buckets, made in the form shown and secured to the faces of the stelliform disks and extending lengthwise of the reel. What may be termed the "floor" or "bottom" a of each of these buckets is made in an obtuse V shape to fit the face of the disks, while the side wall, b, projects outwardly 75 into proximity to the bolting-cloth at such an angle that it readily catches the chop on the ascending side and becomes a deflector on the descending side.

The chop entering at one end of the reel, in 80 the usual manner, is, on falling to the bottom of the reel, carried up on the ascending side of the bolting-cloth until the force of gravity compels it to slide back again, when the buckets, which are in close proximity thereto, catch 85 it and carry it in the further rotation of the device toward the descending side, where the chop is directed by the peculiar shape and formation of the bottom and sides of said buckets to fall quickly against the descending 90 side of the bolting-cloth and reach the bottom again by sliding over the cloth on the descending side of the reel. Thus the intended action of bolting is made to take place over the larger portion of the inside face of the bolting-cloth, 95 and the capacity of the reel is greatly increased thereby.

By adopting the construction shown and described it will be seen that the six-ribbed reel in ordinary use can be readily transformed 100 into my improved reel, as the changes are restricted to the bolting-cylinder alone, and are

carried out by such simple and efficient means that the expense is but small compared with the price of new machines of this class found in the market.

5 What I claim as my invention is—

In a flour-dressing machine, the combination of the following elements: shaft A, radially-located lag-screws B, bolting-cloth C,

disks D, and buckets E, the parts being constructed, arranged, and operating substantially as and for the purposes set forth.

BRUNO KNIFFLER.
